UNITED STATES PATENT OFFICE.

NEWTON S. ATKINS, OF CHARLESTON, WEST VIRGINIA.

AIR-EXHAUSTING DEVICE FOR STEAM-HEATING SYSTEMS.

1,277,820.

Specification of Letters Patent.

Patented Sept. 3, 1918.

Application filed August 25, 1916. Serial No. 116,904.

To all whom it may concern:

Be it known that I, NEWTON S. ATKINS, a citizen of the United States, residing at Charleston, in the county of Kanawha and 5 State of West Virginia, have invented certain new and useful Improvements in Air-Exhausting Devices for Steam-Heating Systems; and I do hereby declare the following to be a full, clear, and exact description of the invention, such as will enable others skilled in the art to which it appertains to make and use the same.

The primary object of this invention is to install in a steam heating system an air 15 exhauster interposed within the return pipe of the system and forming a part thereof and communicating with the discharge flue of the boiler, whereby to admit of the draft through the discharge flue creating a suction 20 within the exhauster, which in turn creates a suction through the return pipe of the heating system and effects withdrawal of the air from the system.

Another object of the invention is the 25 provision of a novel type of exhauster having a float operated valve therein, the said valve having connection with the damper in the discharge flue, and the said exhauster being so positioned within the return pipe 30 that when the steam within the boiler exceeds a predetermined pressure the steam will force water from the boiler into the exhauster and effect heating of the valve, thereby moving the damper to closed position and cutting off the draft through the 35 discharge flue.

Other objects will appear and be better understood from that embodiment of my invention of which the following is a specification, reference being had to the accompanying drawings forming a part thereof, in which:

Figure 1 is a front view of a boiler of the steam heating system, showing the exhauster in operative position in the return pipe and having communication with the discharge flue of the boiler,

Fig. 2 is a top plan view of the exhauster,

Fig. 3 is a section, taken on the line 3—3 50 of Fig. 1,

Fig. 4 is a vertical sectional view, taken through the exhauster,

Fig. 5 is a sectional detail view of the

float operated valve, and showing the same in closed position,

55

Fig. 6 is a detail sectional view of the valve, showing the same in open position.

Referring to the drawings in detail, the letter A designates a boiler of the steam heating system, having the usual discharge 60 flue B, which communicates with a chimney C. The steam dome of the boiler is to be connected up, as usual, with the distributing system, not shown. The return pipe of the system is formed of sections 1 and 2, the 65 section 1 extending horizontally and being connected up in the usual manner with the heating system, and the section 2 is extended vertically and has its lower end communicated by a horizontal branch with the water 70 space in the boiler A.

An air exhauster, designated by the numeral 3, is formed of a vertically disposed cylindrical body having its lower end provided with a nipple 4 that receives the upper end of the section 2 of the return pipe, so as to communicate the water space of the boiler A with the interior of the exhauster 75 3. The exhauster 3 has one side provided with a nipple 5, which is located adjacent the upper end of the exhauster and receives the adjacent end of the section 1 of the return pipe, as is shown more clearly in Fig. 4 of the drawings. The upper end of the exhauster is closed by means of a flanged 80 cap, through which extends a cylindrical shaped valve casing 6, the upper end of the valve casing projecting a slight distance above the cap and threadedly received by one end of the head of a T coupling 7, the 85 stem of the T coupling 7 threadedly receiving one end of a horizontally disposed pipe 8, the opposite end of the pipe 8 extending into the discharge flue B of the boiler. When a draft is created through the dis- 90

charge flue B, the same will create suction in the exhauster 3 by virtue of communication being had between the exhauster and the discharge flue by means of the pipe 8. A vertically reciprocating rod 9 is extended through the casing 6, and has its upper end extended through the upper end of the head of the T coupling 7 and terminally provided with a ring 10 that has connection with a chain 11 that is connected with a suitable 100 operating mechanism, not shown, for the 105

damper (not shown) of the discharge flue. The lower end of the rod 9 extends into a cylindrical valve 12, the said lower end of the stem having connection with a spider 13 mounted within the cylindrical valve and disposed a distance below the upper end of the valve. The upper end of the valve 12 is permanently located within the casing 6, and the said valve is provided with a vertical series of ports 14. The lower end of the valve 12 is closed by means of a head, from the lower surface of which depends a bifurcated member 15. Disposed below the valve 12 is a float 16, the upper end of which is connected to the lower end of a vertically disposed stem 17, the upper end of the stem 17 extending between the fingers of the bifurcated body 15 and pivoted therebetween by means of a pivot pin 18.

20 When the float 16 is in the lowered position, as shown in Fig. 4, the valve 12 will be lowered, so as to locate the openings 14 below the lower end of the casing 6. This lowering of the valve 12 will, by virtue of the rod 9 and the chain 11, operate the damper operating mechanism and open the damper. When the damper is opened the draft created by the chimney C through the discharge flue B will create a suction through the pipe 8 and casing 6, and through the openings 14 in the valve 12, thereby creating a suction within the exhauster 3. The suction created within the exhauster 3 will result in a suction being created through the section 1 of the return pipe, thereby exhausting air from the heating system into the exhauster 3 and through the openings 14 in the valve 12 into the casing 6, and thence out through the pipe 8 and discharged into the flue B. This extraction of the air from the heating system also causes any condensation within the system to be drawn into the exhauster 3 and thence pass from the exhauster through the section 2 of the return pipe 45 to the water space in the boiler A.

If the steam in the steam dome of the boiler A increases beyond a predetermined pressure the same will force water from the boiler A upwardly through the flue of the 50 return pipe into the exhauster 3, and hence move the float 16 upwardly and cause the valve 12 to be moved into the casing 6 so as to cut off communication between the interior of the casing 6 and the exhauster 3.

55 This upward movement of the valve 12 also causes the rod 9 to be moved upwardly and effect operation of the damper operating mechanism, so as to move the damper to closed position and cut off the draft through the discharge flue B. When the steam pressure again reaches normal the water in the 60 exhauster 3 will return to the boiler and admit of the float 16 being lowered, so as to

open the damper, not shown, and the valve 12 and admit of the exhausting operation, 65 above described, being repeated.

By virtue of the vertical series of openings 14 a gradual reduction of the suction in the exhauster 3 will be effected during the raising of the valve 12 by the float 16 when 70 water is forced from the boiler into the exhauster.

The lower end of the casing 6 is provided with a beveled seat 19 and the head on the lower end of the valve 12 has a peripheral 75 beveled flange 20, which is adapted to engage the seat 19, when the valve is moved to its uppermost position, so as to effect a tight joint between the lower end of the valve and the casing, when the valve is in 80 closing position.

A suitable gage glass 21 is associated with the exhauster 3 and serves to admit of the amount of water within the exhauster being determined, the said gage glass having its 85 lower end provided with a discharge cock 22, whereby to admit of the discharge of the water that has been forced into the exhauster, when desired.

It is evident that various changes might 90 be resorted to in the construction, form and arrangement of the several parts without departing from the spirit and scope of my invention: Hence, I do not wish to limit myself strictly to the structure herein described 95 and claimed.

Having thus described the invention what is claimed as new, is:

In a steam heating system, the combination with a steam boiler and a draft flue for 100 the boiler and a radiator return pipe, of an exhauster casing arranged in communication with the return pipe and boiler; a vertical valve casing extending through the upper end of the exhauster casing, a pipe establishing communication between the draft flue of the boiler and the upper end of the exhauster casing and having the upper end of the valve casing secured within it, a 105 cylindrical valve operable within the lower end of the valve casing and open at the upper end and closed at the lower end and provided intermediate of its ends with a vertical series of openings, a float operating within the exhauster casing and connected to the valve, and a vertical damper controlling rod extending through the valve casing into the valve and connected with the latter and piercing the pipe, which connects the exhauster casing with the flue. 110 115 120

In testimony whereof I affix my signature in presence of two witnesses.
